CONVERTIBLE CRIB AND BED

Bernard Greenbaum, New York, N. Y.

Application June 23, 1939, Serial No. 280,784

2 Claims. (Cl. 5—93)

This invention relates to convertible beds, particularly beds for children that can be converted from a crib to a regular bed or a day bed.

Broadly, it is an object of my invention to provide a type of bed that can be converted without additional charge to a regular bed when the child outgrows the crib.

More particularly, it is an object of my invention to provide a type of bed which can be easily and simply converted from one type to another by rearrangement or elimination of parts, provision being made for such conversion.

A further object is to provide a convertible bed or crib of modern structure and appearance which is economical to manufacture and to convert so that such conversion is not easily discernible.

A further object is to provide improved means of joining and disassembly of the parts so that whichever form the bed takes, it will be rigid, firm and of finished appearance.

Another object is to provide a convertible bed which may be knocked down and packed for shipping in a minimum of space and which can be stacked sufficiently compact to prevent damage during shipment over long distances.

For a fuller understanding of the nature and objects of my invention, reference is had to the following detailed description in connection with the accompanying drawing, in which:

Figure 1 is a perspective view of my bed converted to a crib with the headboard and footboard containing the extension pieces which act as the legs.

Fig. 2 is a perspective view of the crib shown in Fig. 1, with the footboard dropped by the removal of the footboard extension converting the crib to a regular bed.

Fig. 3 is a perspective view of the crib and bed shown in Figs. 1 and 2, respectively, with both the headboard and footboard leg extensions removed, converting the crib or bed to a daybed type.

Fig. 4 is an enlarged sectional view taken through line 4—4 of Fig. 1.

Fig. 5 is a perspective view of a headboard or footboard of a modified structure of my convertible bed, showing the side rails broken away.

Referring to the drawing, numeral 10 represents one end of the bed, which for the purpose of clarity I will call the headboard, since it can also be called the footboard. The opposite end 11 is the footboard. Both the headboard 10 and the footboard 11 have dowel holes 12 in their bottom edges and near each of their upright sides, as shown in Fig. 4.

When the bed is converted to a crib, as shown

in Fig. 1, extension leg members 13 and 14, for the headboard and footboard, respectively, are added by inserting dowels 15 at each of the upper ends of the extension leg members 13 and 14 into the coacting dowel holes 12 of the headboard 10 and footboard 11, so that the headboard 10 and footboard 11 are raised the same height.

Dowel holes 16 are provided in sets at the lower ends and near the sides of both the headboard 10 and footboard 11. Side rails 17 of equal length have sets of dowels 18 which are arranged to fit within dowel holes 16 in any of the sets provided in the headboard 10 and footboard 11.

In the crib type shown in Fig. 1, the dowels 18 of the side rails 17 are set within the middle set 15 of dowel holes 16 so that both side rails 17 are at the same level, the headboard 10 and footboard 11 being at the same height.

The sides of both the headboard 10 and footboard 11 are provided with metal rods 19 running vertical and parallel to the sides of the headboard 10 and footboard 11. The upper end 21 of each rod 19 is fastened within screw cap 20 either by a screw thread or other means, while the opposite end 22 passes through eye 24 of screw 23. Screws 23 are screwed into the lower ends of headboard 10 and footboard 11, through the dowels 15 of extension leg members 13 and 14 in order to firmly hold such leg members rigidly in position, as shown in Fig. 4.

Before rods 19 are positioned, slatted side rails 25 having screw eyes 26 are placed in position by passing rods 19 through screw eyes 26. Hooks 27 attached to caps 20 hold side rails 25 in their upper position as shown in Fig. 4. When the side rail 25 is lowered as shown in Fig. 1, springs 28, seated upon screw eyes 24, act against the lowest screw eyes 26 to ease the weight of side rails 25.

Any standard type of spring and mattress may be used with my convertible crib or bed by seating such spring and mattress upon side rails 17.

When sets of holes 16 are not in use, pegs 29 can be placed within the holes 16 to add to the appearance of the bed and to prevent dust from entering the holes.

To convert the crib shown in Fig. 1 to a regular bed, as shown in Fig. 2, rods 19, caps 20, screw eyes 23 and side rails 25 are removed. Extension leg member 14 of the footboard 11 is also removed, thus lowering the footboard 11 by the height of leg member 14, leaving the headboard 10 higher than the footboard 11, as shown by the broken line 30 in Fig. 2. The side rails 17 are repositioned by using the lowest set of holes 16 in the headboard 10 and the highest set of holes 16 in the footboard 11.

in the footboard 11 so that side rails 17 are at the same height and parallel to the floor. The unused holes 16 and the holes of upper cap 20 and screw eyes 23 are filled with removable pegs 29 so that the bed gives a finished appearance.

To convert the crib shown in Fig. 1 or the regular bed shown in Fig. 2 to the day bed shown in Fig. 3, the same pieces are removed as described in the preceding paragraph, with the addition that extension leg member 13 is removed from the headboard 10. The side rails 17 are repositioned by using the upper sets of holes 16 in both the headboard 10 and footboard 11, thus both the headboard 10 and footboard 11 are at the same height and rails 17 are parallel to the floor and are at the same level. The pegs 29 are repositioned to fill only the unused holes.

In the modified type of bed shown in Fig. 5, the same procedure is followed for converting from one type of bed to another, as hereinbefore described with regard to Figs. 1 to 4, inclusive. The modified bed of Fig. 5 has legs 31 and extension legs 32 joined by rail 33. Extension legs 32 have dowels which are removable from legs 31 in a manner similarly described for Figs. 1 to 4, inclusive. Side rails 34 are also repositioned in the different sets of holes 35 as described for Figs. 1 to 4, inclusive and pegs inserted in the unused holes.

It is obvious that my bed may be converted from one type to another and that it may be made in various styles and designs and that modifications may be made in some details of construction without departing from the general spirit of the invention, as set forth in the appended claims.

I claim:

1. A convertible bed of the character described, comprising a headboard and footboard, upper and lower sets of holes in said headboard and footboard, said holes in said headboard and footboard being arranged in registering relation, a pair of removable side rails having protruding dowels, said dowels being arranged to enter said sets of holes respectively, removable extension leg members for said headboard and footboard, whereby when one of said leg members is removed, thereby causing one of said boards to drop, said side rails may be removed and remounted with said dowels inserted into a different set of registering holes in one of said boards and cause said rails to assume a level position.

2. In a convertible bed of the character described, comprising a headboard and footboard, upper and lower sets of holes in said headboard and footboard, said holes in said headboard and footboard being arranged in registering relation, a pair of removable connecting side rails having protruding dowels, said dowels being arranged to enter said sets of holes respectively, removable slatted guard rails having eyes projecting therefrom and being designed to receive rods joined to said headboard and footboard, removable extension leg members for said headboard and footboard, whereby when one of said leg members is removed thereby causing one of said boards to drop, said connecting side rails may be removed and remounted with said dowels inserted into a different set of registering holes in one of said boards and cause said rails to assume a level position and whereby said levelling will permit said guard rails to have free vertical movements.

BERNARD GREENBAUM.
